UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA.

MANIFOLDING SALES-BOOK.

1,174,048.

Specification of Letters Patent.

Patented Mar. 7, 1916.

Application filed July 3, 1912. Serial No. 707,421.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

My present invention relates to manifolding sales books, and particularly to those called triplicate books.

It has for its object to provide a simple, practical device, easily and quickly manipulated, inexpensive to manufacture and of novel construction.

In the accompanying drawing, wherein is shown one of various possible embodiments of this invention.—Figure 1 is a diagrammatic perspective view of a sales book in operative position, with certain parts torn away; and Fig. 2 is a central transverse sectional view. Fig. 3 is a longitudinal section 25 of one of my salesbooks.

Similar reference characters refer to similar parts throughout the different views of the drawing.

Referring now in detail to the drawing, 30 and more particularly to Fig. 1, there is denoted at 1 a back of cardboard or other suitable stiff material whereby the book may be used separately or mounted in a holder of any convenient style, as desired. On this back are mounted a plurality of sets of original and triplicate leaves 2 and 3, respectively, bound together along one end edge by means of staples 4 to the back 1.

Both the original and triplicate leaves of 40 each set are separated from the stub 5 by lines of perforations 6, whereby they may be easily and quickly detached therefrom.

It is, of course, to be understood that these leaves may also be suitably ruled and spaced 45 in any desired manner, according to the use to which the book is to be put.

Secured to the lower end or free edge 7 of original leaf 2 is a thin semi-transparent duplicate leaf 8 of tissue or parchment. 50 This leaf in size is substantially equal to the body portion of the other leaves; that is, it terminates just short of the stub 5, or adjacent the line of perforations.

Secured to the upper surface and along 55 one of the side edges of the back 1 is a

double-faced carbon sheet 9 which extends upwardly along the side of the pad, and thence transversely across the original leaf 2 and below the tissue leaf 8. It is thus seen that when an impression is made upon the original leaf it will be transferred by one of the carbon faces to the leaf 3 therebeneath, and also to the under side of the tissue leaf 8 by means of its upper carbon surface. The tissue leaf being semi-transparent, of course, enables the inscription to be read therethrough. By mounting the carbon sheet in this manner, it always completely covers the original leaf, and as the pad becomes reduced in thickness it will tend to creep toward the right side of the book, as shown in Fig. 1, thereby completely covering the usual "cents" column, as well as providing, to a certain extent, a fresh carbon surface for this column.

Having described the construction of one embodiment of the invention, a convenient method of operating the same is substantially as follows: Assume the book to be in the position shown in Fig. 1, the inscription is made upon the upper surface of the original leaf 2, which is reproduced in duplicate and triplicate upon the respective leaves, as above set forth. The original and tissue leaves are then torn from the stub along the line of perforations 6 and the carbon sheet 9 removed from above the duplicate leaf, whereupon the remaining leaf may be detached in a similar manner. The next original leaf with the tissue leaf attached thereto is swung upwardly and the carbon sheet laid therebeneath, whereby the book is again ready for subsequent operations. After the leaves have been detached from the book they may be separated and disposed of according to the rules of the establishment.

It is thus seen that this invention provides a simple and practical triplicate sales book adapted to accomplish, among others, all of the objects and advantages above set forth.

Having thus described my invention, what I claim as new and desire to secure by Letters Patent is:

1. A manifolding sales book comprising a back, a stub portion attached to the back, an original sheet, a tissue duplicate sheet, a triplicate sheet, and a double faced carbon sheet between the latter two sheets; one edge

of the original sheet being detachably secured to the stub portion, and the opposite edge thereof being attached to the tissue sheet, an edge of the triplicate sheet being 5 also secured to the stub.

2. A manifolding sales book comprising a back, a stub portion, an original sheet upon which entries are to be made, a tissue sheet upon the back of which said entries are 10 duplicated, a third sheet upon which they are triplicated, and a double-faced carbon sheet disposed between the tissue sheet and

the triplicate; the original sheet having one end thereof detachably secured to the stub portion, the triplicate sheet being also so secured, and the tissue sheet being secured at one end to the unbound end of one of the other sheets. 15

In testimony whereof I affix my signature, in the presence of two witnesses.

EDWARD KIRBY BOTTLE.
